Albert A. Henzi, Inventor:
By Adams & Jackson, Atty's.

UNITED STATES PATENT OFFICE.

ALBERT A. HENZI, OF CHICAGO, ILLINOIS, ASSIGNOR TO THE GOSS PRINTING PRESS COMPANY, OF CHICAGO, ILLINOIS, A CORPORATION OF ILLINOIS.

CHASE.

1,162,861.

Specification of Letters Patent.

Patented Dec. 7, 1915.

Application filed February 27, 1915. Serial No. 10,932.

To all whom it may concern:

Be it known that I, ALBERT A. HENZI, a citizen of the United States, residing at Chicago, in the county of Cook, State of Illinois, have invented certain new and useful Improvements in Chases, of which the following is a specification, reference being had to the accompanying drawing.

This invention relates to chases and particularly to the means provided for locking a form in the chase.

It is the principal object of my invention to provide an arrangement of parts by which the form can be very quickly and easily locked in position in the chase.

It is another object of my invention to improve devices of this type in sundry details hereinafter pointed out.

The preferred means by which I have accomplished my objects, by which I am enabled to lock the form in the chase by a single operation of a single part, are illustrated in the accompanying drawings and are hereinafter specifically described.

That which I believe to be new and wish to cover by this application is set forth in the claims.

In the drawings:—Figure 1 is a top or plan view of a construction embodying the preferred form of my improvements, two of the sides of the chase there shown being broken away; Fig. 2 is a detail, being a section taken on line 2—2 of Fig. 1; and Fig. 3 is a top view of a modified form of construction, being also partly broken away.

Referring to Figs. 1 and 2, in which corresponding parts are indicated by the same reference characters,—10 indicates a chase provided with a foot-stick 11 and a side-stick 12, by which the form is adapted to be suitably locked in the chase, as will be readily understood, the side-stick 12 being adapted to be brought into firm engagement with the end of the foot-stick 11. The bottom bar of the chase 10 is milled out at a plurality of points along its inner edge to provide for the insertion of links 13 which are pivotally secured in position therein by means of pins 14. The opposite ends of the links 13 are inserted in recesses milled out of one edge of a bottom locking-bar 15 where such links are pivotally secured by means of pins 16, whereby the bottom locking-bar 15 is adapted by its longitudinal movement to be moved toward and from the

bottom bar of the chase. The outer edge of the side-stick 12 is also milled out at a plurality of points to provide for the insertion of links 17 which are pivotally secured in the milled out recesses by means of pins 18. The opposite ends of the links 17 are inserted in suitable recesses milled out of the inner edge of a side locking-bar 19, in which recesses the links are pivotally mounted by means of pins 20. With the side locking-bar 19 in engagement with the side-bar of the chase, a movement of the side locking-bar 19 longitudinally of itself in the direction to bring the links 17 more nearly into perpendicular position relative to said locking-bar serves to move the side-stick 12 to the right in Fig. 1, as will be readily understood.

21 indicates a screw secured by means of screw-threads in the end of the bottom locking-bar 15 adjacent to the side-stick 12, said screw being provided with one or more sockets 22 by means of which the screw can be turned by any suitable pin wrench. Mounted by means of screw-threads in the bottom-bar of the chase in alignment with the side locking-bar 19 is another screw 23 provided with an angular head 24 by which the screw may be turned by any suitable tool.

With the screw 21 in proper adjusted position relative to the locking-bar 15, and with the foot-stick 11 and the side-stick 12 both in retracted position, a form is adapted to be placed in the chase 10. Thereupon through the action of the screw 23 the form is adapted to be locked firmly in position, the side-stick 12 being moved to the right in Fig. 1 by reason of the longitudinal movement of the side locking-bar 19 as actuated by the advancing screw 23, and the foot-stick 11 being moved inward toward the form by reason of the movement of the bottom locking-bar 15 to the right in Fig. 1 as actuated by the screw 21 in engagement with the side-stick 12. As will be readily understood, after the locking of the side-stick 12 by means of the screw 23 the foot-stick 11 can be still further tightened by a proper rotation of the screw 21, but with the screw 21 in proper adjustment before the locking operation, the operation of locking the side-stick by means of the screw 23 serves simultaneously to lock the foot-stick.

The side-stick 12, the foot-stick 11, and

the side bars of the chase opposite to said two sticks, are chamfered at their upper inner edges to enable them to have the desired bearing upon the type, such chamfers 5 being preferably of the character shown 25 in connection with the foot-stick 11 in Fig. 2. The foot-stick 11 is provided at intervals along its inner edge with notches 26 adapted to receive the ends of the column 10 rules of the form for holding the rules in vertical position for the placing of the type between them. The engaging edges of the side locking-bar 19 and the side-bar of the chase adjacent thereto are also cut out for 15 a greater part of the length of said bars in order to reduce the frictional contact between such parts to a minimum, the adjacent engaging edges of the bottom locking-bar and the foot-stick being also similarly 20 cut away.

In Fig. 3, which shows a modified form 25 of construction, the parts which correspond to those above described are indicated by the same reference characters but with the addition of an exponent *a*. In this construction, a pair of bottom locking-bars 27—28 are provided adapted to be removed from the frame of the chase if desired. Such bars are milled out on their adjacent edges 30 to receive links 29 which are pivotally connected to the bars by suitable pivot pins 30, whereby the locking bars are adapted to be forced away from each other by a suitable longitudinal movement of the bar 28 35 by a screw 21^a corresponding to the screw 21 as above described, serving thus to move the foot-stick 11^a into proper locking position in the manner above described.

What I claim as my invention and desire 40 to secure by Letters Patent, is—

1. In a chase, the combination of a side-stick, means for moving said side-stick into locking position, a foot-stick, and means actuated by the locking movement of the 45 side-stick for moving said foot stick into locking position, said last-named means being adapted to be adjusted for moving the foot-stick into or out of locking position independently of any movement of the side- 50 stick.

2. In a chase, the combination of a side-stick, means for moving said side-stick into locking position, a foot-stick, a bottom locking-bar by a longitudinal movement of 55 which said foot-stick is moved into locking position, and a screw interposed between said bottom locking-bar and said side-stick for causing them to move together for locking purposes, said screw being adapted by 60 its adjustment to vary the movement of the foot-stick relative to that of the side-stick.

3. In a chase, the combination of a side-stick, means for moving said side-stick into 65 locking position, a foot-stick, a bottom lock-

ing-bar movable longitudinally of itself alongside of said foot-stick, a plurality of links pivotally connected with said locking-bar serving to cause the bar to move edge-wise toward or away from the said foot-stick when the bar is moved longitudinally, and means actuated by the locking movement of the side-stick for moving said bottom locking-bar longitudinally in the same direction. 75

4. In a chase, the combination of a side-stick, means for moving said side-stick into locking position, a foot-stick, a bottom locking-bar adapted to engage said foot-stick, links pivotally mounted on the bottom-bar 80 of the chase and pivotally connected with said locking-bar whereby a movement of the locking-bar longitudinally of itself serves to move it toward or away from the bottom bar of the chase, and means actuated by the locking movement of the side-stick for moving said bottom locking-bar away from the bottom-bar of the chase. 85

5. In a chase, the combination of a side-stick, means for moving said side-stick into locking position, a foot-stick, a bottom locking-bar adapted to engage said foot-stick, links pivotally mounted on the bottom-bar 90 of the chase and pivotally connected with said locking-bar whereby a movement of the locking-bar longitudinally of itself serves to move it toward or away from the bottom bar of the chase, and a screw interposed between said bottom locking-bar and said side-stick for causing them to move together 95 whereby upon a locking movement of the side-stick said foot-stick is also moved into locking position. 100

6. In a chase, the combination of a side-stick, a side locking-bar located alongside of said side-stick, links pivotally connecting said side-stick with said side locking-bar whereby a movement of the locking-bar toward the top of the chase serves to move the side-stick into locking position, a foot-stick, a bottom locking-bar adapted to engage said foot-stick, links pivotally connecting said bottom locking-bar with said chase whereby a movement of the said bottom locking-bar away from the side of the chase at which said side-stick is located serves to move the foot-stick into locking position, and means actuated by the locking movement of the side locking-bar for giving said bottom locking-bar an operative 115 locking movement. 120

7. In a chase, the combination of a side-stick, a side locking-bar located alongside of said side-stick, links pivotally connecting said side-stick with said side locking-bar whereby a movement of the locking-bar toward the top of the chase serves to move the side-stick into locking position, a foot-stick, a bottom locking-bar adapted to engage said foot-stick, links pivotally connecting said 125

bottom locking-bar with said chase whereby a movement of the said bottom locking-bar away from the side of the chase at which said side-stick is located serves to move the 5 foot-stick into locking position, a screw interposed between said bottom locking-bar and said side-stick for causing them to move together upon an operative locking

movement of the side-stick, and a screw interposed between said side locking-bar 10 and said chase for giving said side-locking-bar an operative locking movement.
